INTERFERENCE ELIMINATION

Vivian Cohen Henriquez and Bernardus Dominicus Hubertus Tellegen, Eindhoven, Netherlands, assignors to Radio Corporation of America, a corporation of Delaware

Application April 15, 1936, Serial No. 74,428
In Germany May 14, 1935

3 Claims. (Cl. 250—20)

This invention relates to an improved method of eliminating interference in the wireless transmission of intelligence.

For the suppression of atmospheric disturbances and the like in the reception of intelligence transmitted by wireless it has previously been proposed to render the high or intermediate frequency amplifier of the receiving apparatus inoperative when such disturbances arise, either by automatically increasing, when interference occurs, the damping of the tuned high or intermediate frequency circuits or by reducing the amplification of the high or intermediate frequency amplifying tubes by means of a variation 10 of the grid bias.

However, these known methods do not lead to the purpose in view as when the high or intermediate frequency portion of the receiver is rendered inoperative the interference proper is suppressed, it is true, but at the same time the carrier wave of the signal received is also suppressed with the result that necessarily at the 20 demodulation rectifier of the receiver a new disturbance is set up which becomes perceptible in the reproducing apparatus.

This adverse condition renders the effect of the above described method of eliminating interference illusive. It is, therefore, an object of our invention to provide means for avoiding the aforementioned difficulties. The transmission of the communications to be transmitted is effected, in accordance with the invention, in such manner that in the transmitter or in the receiver the carrier wave is suppressed when interference occurs, and then the high or intermediate frequency portion of the receiver is made inoperative.

Circuit arrangements for the suppression of the carrier wave and, if desired, of a side band on the side of the transmitter are known. In 40 one of these known circuit arrangements the modulation stage of the transmitter consists for example, of two tubes in push-pull connection to the control grids of which the high frequency is supplied cophasally whereas the low frequency to be modulated on the high frequency is supplied counterphasally. In this case one obtains in the output circuit of the modulation stage a modulated high frequency in which the carrier 45 wave is suppressed.

Circuit arrangements for the suppression of the carrier wave in the receiver are also known. In these arrangements use is frequently made of filters composed of piezo-electric crystals.

Whether the carrier wave is suppressed on the

side of the transmitter or on the side of the receiver, in either case it has to be added again in the demodulation stage by generating this carrier wave anew in the receiver by means of a suitable generator.

The accompanying drawing shows, by way of example, two preferred embodiments of the invention. Fig. 1 is a circuit diagram illustrating one mode of execution, while Fig. 2 shows an alternative circuit arrangement, both embodiments, however, being for the elimination of interference in which the carrier wave is suppressed on the side of the receiver.

Into the input circuit of a high frequency amplifier H. F. is connected a filter F which suppresses the carrier wave of the signal received and passes the modulation side bands. The latter are amplified in the high frequency amplifier H. F. and supplied, together with the oscillations generated by a local oscillator O, to a demodulation rectifier G₁, the frequency of said local oscillation being equal to that of the suppressed carrier wave.

The rectifier G₁ is followed by a low frequency amplifier N. F. and by a reproducing apparatus, for example, a loudspeaker L. 25 A connection is tapped from the output circuit of the high frequency amplifier to an auxiliary rectifier H which has a threshold value such that in the absence of interference no current flows in the rectifier. When a disturbance of suitable 30 value arises the threshold value is surpassed and a current flows in the rectifier. This current controls the amplification of the high frequency amplifier by a grid bias variation of the amplifying tubes in such manner that the amplification 35 is reduced and that the interference has no effect in the next portion of the receiver. In order to ensure that the circumstance that the high frequency amplifier is suddenly rendered inoperative does not give rise to new interference due 40 to the fact that the tuned oscillatory circuits of the amplifier are excited in their natural frequency, it is advantageous to connect a filter F₁ into the lead going from the auxiliary rectifier to the high frequency amplifier. The task of 45 said filter is to suppress that frequency component comprised in the voltage impulse supplied by the auxiliary rectifier to the grids of the amplifying tubes, whose frequency corresponds to the natural frequency of the tuned oscillatory circuits of the amplifier. The filter F₁ may consist, 50 for example, of a tuned oscillatory circuit which is tuned to the same frequency as is the high frequency amplifier. Better results than those afforded by the circuit arrangement shown may

be obtained if the auxiliary rectifier H is controlled by an auxiliary receiver or amplifier; for example, the auxiliary rectifier H may be connected via an amplifier AA before or behind the filter F. The time constants of the auxiliary amplifier and of the auxiliary rectifier H must therefore be so dimensioned that the high frequency amplifier H. F. is made inoperative before the interference attains said amplifier. If desired, an electric time lag or delay circuit DC may be connected between the filter F and the high frequency amplifier H. F.

We claim:

1. A radio receiver having a filter for damping the carrier component of an incoming modulated wave, a high frequency amplifier fed with energy from said filter, a local oscillator and de-modulator for deriving a low frequency wave from the output of said amplifier, a utilization device fed with said low frequency wave, an auxiliary rectifier connected to the output circuit of said high frequency amplifier, and means including a resonant circuit tuned to the frequency of said high frequency amplifier and connecting between the input side thereof and the output side of said auxiliary rectifier for blocking said amplifier

in response to interfering and static energy.

2. A radio receiver having a filter for damping the carrier component of an incoming modulated wave, a main high frequency amplifier fed with energy from said filter, a local oscillator and de-modulator for deriving a low frequency wave from the output of said amplifier, a utilization device fed with said low frequency wave, means including an auxiliary rectifier having an output circuit connected to a resonant circuit and thence to the input side of said high frequency amplifier for blocking said amplifier in response to interfering and static energy, said resonant circuit being tuned to the frequency of said high frequency amplifier, and means including a circuit fed with said interfering and static energy for actuating said auxiliary rectifier.

3. A radio receiver in accordance with claim 1 and having a delay circuit interposed between said filter and said main high frequency amplifier and an auxiliary amplifier in the last said means.
